R. A. FRY

RAILWAY TRACK INSTRUMENT

Filed June 23, 1923

Patented June 2, 1925.

1,539,939

UNITED STATES PATENT OFFICE.

ROY A. FRY, OF OMAHA, NEBRASKA.

RAILWAY-TRACK INSTRUMENT.

Application filed June 23, 1923. Serial No. 647,359.

To all whom it may concern:

Be it known that I, ROY A. FRY, a citizen of the United States, residing at Omaha, in the county of Douglas and State of Nebraska, have invented certain new and useful Improvements in Railway-Track Instruments, of which the following is a specification.

My invention relates to railway signalling devices, and particularly to track-instruments such as are employed for controlling crossing-signals and the like, by closing or opening an electrical circuit upon the approach of a train to the crossing. It is the object of my invention to provide a simple, inexpensive and positively operated track-instrument, actuated solely by the deflection of a track-rail under the weight of a locomotive or car, whereby to insure durability of the mechanism, due to the elimination of hammering blows upon the parts by the impact of wheels thereon, and to insure stability of adjustment due to the uniformity of action of the relatively movable parts which actuate the mechanism. A further object of my invention is to provide a track-instrument of the general character above stated, which may be employed to give a selective indication, dependent upon the direction of movement of the rail-deflecting body.

In the accompanying drawings, Fig. 1 is a side view of a track-instrument embodying my invention, Fig. 2 is a detail side view of a portion of the same, with the side-plate or cover removed, Fig. 3 is a detail side view of the jack-switch, Fig. 4 is a transverse section of the track-rail on the line 4-4 of Fig. 1, showing the track-instrument in end elevation, Fig. 5 is a detail transverse section on the line 5-5 of Fig. 2, Fig. 6 is a detail side view of the tilting lever, and Fig. 7 is a detail horizontal section on the line 7-7 of Fig. 4.

In carrying out my invention I make use of the well-known fact that a railway track is appreciably deflected during the passage of a locomotive or car along the same, regardless of the size of the rails or of the condition, as to solidity or otherwise, of the roadbed. Such rail-deflections have been heretofore utilized for the operation of track-instruments, by devices which amplify the relative movements of the rails and ties, or of the rail and some other member which is supported upon the roadbed so as to be substantially independent of the track.

proper. The movements of the track-rails relative to the ties or roadbed are variable, both as to the amount of motion and as to the normal positions of the parts assumed when the rails are not loaded, according to the condition of the roadbed and the rigidity of the fastenings between the rails and ties, so that it is difficult to provide instruments capable of utilizing such movements to give a dependable signal indication, without constant inspection and readjustments to compensate for the variations. To avoid the difficulties above mentioned, I so construct my track-instrument as to actuate the same solely by the actual deflection of the track-rail between definitely spaced points thereon, as shown by the motion of the rail intermediate said points relative to a rigid beam which is fixedly connected with and supported upon the rail at said points.

Referring to the drawings, there is represented one of the rails 8 of a railway track, which rests upon and is secured to ties or sleepers 9 in the usual way. Alongside the rail there is disposed the rigid bridge-beam 10, which may be a rolled steel I-beam, said beam 10 being supported at its ends only, which are secured to the rail by means of bolts 11 passing through the web portions of the beam and rail, the webs being held in properly spaced relation by means of sleeves or spreaders 12, as indicated in Fig. 4. The upper side of the beam 10 is far enough below the tread or upper face of the rail to avoid possibility of the beam being engaged by any portion of the wheels of a train passing along the track. The length of the beam 10 is made such that when the rail is deflected by the weight of a car or locomotive upon the span intermediate the beam-supporting points or bolts 11, there will be an appreciable relative movement of said intermediate portions of the rail and beam, due to the fact that the beam will not be deflected by supporting any portion of the load. In practice, it is found that with standard railway track construction a length of twelve feet between the rail-supported points of the bridge-beam 10 is sufficient to secure effective operation of the mechanism.

To operate the signal-controlling devices, the relative movements of the rail and bridge-beam are amplified by means of levers 13 and 13'. Said levers are pivoted on the outer side of the bridge-beam, at points intermediate the center and ends of said beam,

2 1,539,939

by means of pins 14 affixed to and extending laterally from the web of the beam, as shown. The levers are preferably L-shaped in transverse section and may be formed 5 from rolled steel angle-bars, the vertical flanges thereof being tapered or gradually reduced from the pivoted ends toward the free or movable ends of the levers, and the extreme end portions 15 and 15' being pointed and curved slightly downward, said portions 15 and 15' being adjacent to each other as shown. The lateral extent of the levers 10 13 and 13' is such that they do not project beyond the outer flanges of the bridge-beam 10, and preferably a cover-plate 16 is secured against the edges of said flanges, as shown, to form a protective housing for the levers and the parts associated therewith. Adjacent to the pivoted end of each lever 15 20 there is a vertical bolt 17 which passes loosely through the horizontal flange of the lever and extends slidably through an opening in the lower flange of the beam 10. The lower end of the bolt is connected with the rail by 25 means of the clamp-bracket shown in Figs. 4 and 7, said bracket comprising a bar 18 which passes beneath the rail and has a hooked end-portion fitting about the opposite flange thereof, a second bar 19 having an 30 offset portion which engages the upper side of the adjacent rail-flange, and a screw 20 which secures together the laterally projecting portions of the bars. Between the 35 clamp-screw 20 and the rail-flange the bars 18 and 19 have registering slots 21 through which the bolt 17 extends. At points intermediate the bolts 17 and the curved ends 15-15' of the levers, the horizontal flanges of the latter have openings for the passage of 40 bolts 22. Said bolts extend through the upper flange of the bridge-beam 10, so as to be suspended therefrom, and at their lower ends are provided with adjusting-nuts 23. Between said nuts and the lower sides of the 45 levers are coil spring 24 which press upwardly upon the levers and normally hold the movable ends 15-15' up against the upper flange of the beam 10. Downward movement of the levers is limited by pins 25 and 50 25' which project laterally from the web of the bridge-beam beneath the lever-ends 15 and 15', as best indicated in Fig. 6. It will be seen that a very slight depression of the rail relative to the bridge-beam at points adjacent to the connecting-bolts 17, will result 55 in a greatly amplified movement at the ends 15-15' of the levers. Should such movement be more than enough to carry the lever-ends from the upper stop, formed by the 60 flange of the bridge-beam, to the lower stop formed by the pins 25-25', the excess movement is accommodated by a slight bending of the levers, which should be of material sufficiently resilient to permit such bending 65 without permanent distortion.

On the web of the bridge-beam 10 beneath the ends 15-15' of the levers, there is a laterally projecting pin 26 on which is pivotally mounted a tilting-lever having substantially horizontal arms 27 and 28, and 70 a vertical arm 29 of which the upper end is divided to form fingers 30 and 30' having oppositely curved inner sides. A coil spring 31 is connected with the end of the arm 27 and extends to a pin 32 mounted on the beam 10, the tension of said spring normally holding the lever in a position such that the curved inner faces of the fingers 30 and 30' are directly beneath the end portions 15-15' of the levers, but the spring permitting movement of the tilting-lever in either direction from said normal position. The third lever-arm 28 carries a block 33 of insulating material adapted to engage the spring 34 of a jack-switch. In the structure 80 shown the jack-switch consists of a pair of insulating blocks 35 which are secured to the side of the beam 10, the spring 34 being clamped between them, springs 36 and 37 being secured respectively upon the upper 85 and lower sides of the blocks, the springs and blocks being held together by bolts 38 and 39 which are electrically connected, respectively, with the upper and lower springs and insulated from the other springs. The 90 springs 34, 36 and 37 may form the terminals of electrical circuits for controlling any desired signal mechanism, and in the illustrated structure a circuit is normally closed between the springs 34 and 36, and normally 95 open between the springs 34 and 37. In the lower flange of the beam 10 is a nipple 40 through which the wires 41 from the jack-switch are carried.

The operation of the mechanism will be 105 apparent from Figs. 2 and 6. A wheel A moving to the left along the rail 8, as indicated at the right of Fig. 2, will first cause a deflection of that portion of the rail adjacent to the amplifying-lever 13', so that the 110 end 15' of said lever will be moved downwardly to engage the adjacent finger 30' of the tilting-lever, causing said lever to be tilted to the right, whereby the arm 28 will be moved downward, the insulating block 115 33 engaging the spring 34 of the jack-switch and bending said spring to disengage the same from the contact-spring 36 and engaging the same with the spring 37. When the wheel has moved past the center of the 120 bridge-beam, as to the position B indicated by dotted lines in Fig. 2, the lever 13 will also be actuated and moved down to the dotted-line position shown in said figure. Such movement of the lever 13 will not engage the end 15 with the tilting-lever, however, because of the previous movement of the tilting-lever, which is maintained in its first position by the continued depression of 125 the lever 13'. In the case of a wheel mov- 130

ing in the opposite direction, the lever 13 is first depressed, the tilting-lever being thereby moved to the position shown by dotted lines in Fig. 6, and the subsequent movement of the lever 13' having no effect. It will thus be seen that the tilting-lever is operated selectively, according to the direction of movement of the rail-deflecting body, and such selective operation of the tilting-lever may be employed to operate a jack-switch or any other suitable device through which the control of signal mechanism or the like may be effected.

Now, having described my invention, what I claim and desire to secure by Letters Patent is:

1. In a railway track-instrument, the combination with a track-rail, of a long rigid beam disposed alongside the rail, means fixedly connecting the ends of said beam with adjacent parts of the rail, an amplifying-lever fulcrumed on said beam, and means connecting with the rail a part of said lever adjacent to its fulcrum, whereby a slight relative movement of the rail and beam at the point of said connection may effect a large movement of the free end of the lever.

2. In a railway track-instrument, the combination with a track-rail, of a long bridge-beam having its ends fixedly secured to the rail and being supported wholly thereby, levers fulcrumed on said bridge-beam and connected with the rail so as to be actuated successively by deflections of the rail from a moving load thereon, and means actuated by said levers selectively according to the direction of movement of the rail-deflecting load.

3. In a railway track-instrument, the combination with a track-rail, of a long bridge-beam disposed alongside the rail and supported wholly thereon by fixed connections between the same at the ends of the bridge-beam, levers fulcrumed on the bridge-beam at longitudinally spaced points intermediate its ends, the free ends of said levers being movable in proximity to each other, means connecting portions of the levers adjacent to

the fulcrums thereof with the contiguous portions of the rail, whereby deflections of the rail relative to the bridge-beam will actuate said levers, and means positioned near the free adjacent ends of said levers and movable oppositely thereby, whereby upon actuation by either of the levers said means will be displaced from the path of the other lever.

4. In a railway track-instrument, the combination with a track-rail, of a long rigid beam disposed alongside said rail, means fixedly connecting the ends of said beam with the rail to support the same thereon, amplifying levers fulcrumed on said beam at points intermediate the ends and center thereof, said levers having terminal portions adjacent to the center of the beam, means for connecting to the rail portions of the levers adjacent to the fulcrums thereof so that slight movements of the rail relative to the beam will cause larger movements of the terminal portions of the levers, and a tilting lever positioned so as to be normally engageable by the terminal portion of either of the amplifying levers, said tilting lever being movable by either amplifying lever to a position at which it is not engageable by the other.

5. In a railway track-instrument, a pair of amplifying levers having adjacent terminal portions, means connecting said levers with longitudinally spaced portions of a track-rail, whereby the levers are actuated successively by progressive deflection of the rail such as caused by the movement of a load along the same, a tilting lever positioned in proximity to said terminal portions of the amplifying levers, resilient means normally holding a part of the tilting lever in position for engagement by either of said terminal portions and arranged to enable movement of said lever in either direction from said normal position, and means actuated by said tilting lever selectively according to the direction of movement thereof from said normal position.

ROY A. FRY.
